(57) **CLAIM**

The ornamental design for an ergonomic key presser for keyboard as shown and described.

DESCRIPTION

FIG. 1 is a top, front, right side, perspective view of an ergonomic key presser for keyboard according to the present invention;

FIG. 2 is a bottom rear right side perspective view of the ergonomic key presser for keyboard of FIG. 1;

FIG. 3 is a bottom plan view of the ergonomic key presser for keyboard of FIG. 1;

FIG. 4 is a top plan view of the ergonomic key presser for keyboard of FIG. 1;

FIG. 5 is a right side elevation view of the ergonomic key presser for keyboard of FIG. 1;

FIG. 6 is a left side elevation view of the ergonomic key presser for keyboard of FIG. 1;

FIG. 7 is a rear elevation view of the ergonomic key presser for keyboard of FIG. 1; and,

FIG. 8 is a front elevation view of the ergonomic key presser for keyboard of FIG. 1.
